FASTENING INSERTING MACHINE

Fred N. La Chapelle, Beverly, Mass., assignor to
United Shoe Machinery Corporation, Paterson,
N. J., a corporation of New Jersey

Application July 20, 1934, Serial No. 736,271

31 Claims. (Cl. 1—30)

This invention relates to fastening inserting machines and is illustrated herein as embodied in a machine particularly adapted to insert paper pegs in the manufacture of boots and shoes.

5 Machines particularly adapted for the insertion of paper pegs (now commonly known as fibre fastenings) of the character disclosed and claimed in United States Letters Patent No. 1,729,169, granted September 24, 1929, on an application filed in my name, are being extensively and successfully used. When inserting a peg of the type above referred to, it is necessary first to form a hole in the work piece to receive a peg which is then driven into the hole. In 10 some types of machines separate tools are used to form the holes and to insert the pegs in the holes. Such machines are extensively used and are satisfactory, particularly when the hole forming means is utilized to feed the work past the fastening inserting means. In other types of machines a single tool is used to form the fastening receiving hole and to insert the fastening in the hole. Machines of this latter type operate satisfactorily but it is necessary to provide a relatively complicated mechanism for imparting the 15 proper reciprocating movements to the tool.

It is an object of the present invention to provide a simple and reliable fastening inserting machine having a tool which acts both as an awl and as a driver, well adapted for use in the manufacture of boots and shoes. To this end the illustrated machine, which comprises a preferred embodiment, is provided with an operating tool which acts both as an awl and as a driver, means 20 for reciprocating the tool, and connections between the tool and the reciprocating means including a member yieldably connected to the tool and adapted to move relatively to the tool after the tool has penetrated the work piece to form a fastening receiving hole thereby permitting the tool to be withdrawn from the work during the early portion of the movement of said reciprocating means toward the work, and means acting during a later portion of said movement to move 25 the tool toward the work to insert a fastening in the fastening receiving hole. As illustrated, the connections between the tool and the means for reciprocating the tool include a latch carried by the reciprocating means constructed and arranged to transmit movement of the reciprocating means to the tool carrier during the early portion of the movement of the reciprocating means toward a work piece to form a fastening receiving hole in the work piece and means normally 30 maintaining the latch in engagement with the

carrier and arranged to yield to permit relative movement between the tool carrier and the reciprocating means after the tool has formed a fastening receiving hole in the work piece. The connections include also means in the form of a lever pivoted to the reciprocating means and having one arm arranged to engage cam surfaces on the frame of the machine after the tool has penetrated the work, said lever having another arm engaging the tool carrier and arranged to withdraw the tool from the work, and a projection formed on said reciprocating means arranged to engage the tool carrier to move the tool toward the work to insert a fastening in the hole during a later portion of the movement of the reciprocating means toward the work. The illustrated machine is provided with means for severing a fastening from a length of fastening material and for transferring the severed fastening into the path of movement of the operating tool just prior to the fastening inserting operation.

With the above and other objects and features in view the invention will now be described with reference to the accompanying drawings and 25 pointed out in the appended claims.

In the drawings,

Fig. 1 is a view in side elevation of a machine embodying a preferred form of the invention;

Fig. 2 is a sectional view of the fastening inserting mechanism taken along the line II—II of Fig. 1;

Fig. 3 is a detail view of the presser plate and the fastening severing and feeding mechanism;

Fig. 4 is a view similar to the one shown in Fig. 2 showing the fastening inserting mechanism at the conclusion of the awl stroke;

Fig. 5 is a view similar to Fig. 4 showing the fastening inserting mechanism at the conclusion of the fastening inserting stroke;

Fig. 6 is a side view of the mechanism for actuating the fastening inserting mechanism and the fastening severing and feeding mechanism;

Fig. 7 is a front view of the mechanism shown in Fig. 6;

Fig. 8 is an enlarged detail front view of the fastening inserting mechanism shown in Fig. 2; and

Fig. 9 is an enlarged detail view of the mechanism carrying the fastening inserting tool.

In the illustrated embodiment of the invention the machine is provided with a column 10 which supports the operating instrumentalities of the machine. A head 12 is secured to the column 10 and carries the fastening inserting instrumen- 55

talities. The head 12 is provided with a main shaft to one end of which is secured a treadle controlled stopping and starting mechanism of the type disclosed in United States Letters Patent No. 1,291,754, granted January 21, 1919, on application of Matthias Brock. The other end of the shaft carries a cam 14 which is constructed and arranged to raise an actuating bar 16 which will hereinafter be more particularly described.

10 The head of the machine is also provided with a reel 18 which carries fibre fastening material 20. The fibre fastening material 20 is fed between a pair of feed rolls 22 (Fig. 1) into a tube 24 which terminates at a point adjacent to a movable peg shearing and transfer plate 26 (Figs. 2 and 3). The plate 26 is provided with a fastening receiving hole 27 into which the fastening material is fed. A stationary block 28 lies just above the plate 26 and co-operates therewith to shear the peg from the string of fastening material. The mechanism for feeding the fastening material to the plate 26 need not be described in detail in this application since it is fully described in United States Letters Patent No. 1,327,196, granted January 6, 1920, on application of Matthias Brock. It is to be understood, however, that any other suitable feeding mechanism could be employed if so desired.

It should be noted that although the machine is illustrated herein as provided with a spring-driven fastening inserting mechanism which will now be described, it could be provided with any other suitable means for operating the fastening inserting mechanism. The cam 14 (Fig. 1) lifts the actuating bar 16 against a spring 32 and when the cam 14 has been rotated a sufficient distance a projection on the actuating bar 16 drops off the cam 14 and the driver bar is forced downwardly under the influence of the spring 32 to perform the fastening inserting operation.

The actuating bar 16 (Figs. 2 and 4 to 8) is connected to a tool 34 (Figs. 2, 4 and 5) operating both as an awl and as a driver, the connection being so constructed and arranged that a single movement of the actuating bar 16 in one direction will cause the tool 34 to form a fastening receiving hole in the work, withdraw the tool from the work and then move the tool toward the work to insert a fastening in the hole. Return movement of the actuating bar 16 will return the parts to their original position in preparation for a repetition of the cycle of operation of the machine.

55 Mounted on the front of the head 12 of the machine is a supporting member or frame 40 which is provided with ways in which the actuating bar 16 is reciprocated. The lower end of the frame 40 carries a presser plate 42, best shown in Figs. 2 and 3, which is secured to the frame 40 by means of cap screws 44. The lower end of the actuating bar 16 carries a latch 46 (Figs. 2 and 4 to 8) which is mounted for movement in ways formed in the lower end of the actuating bar. The latch 46 is urged forwardly by a plunger 48 (Figs. 2, 4 and 5) mounted in a hole formed in the rear portion of the frame 40, the plunger being urged forwardly by a spring 50. The pressure of the spring 50 may be increased or decreased by an adjusting screw 52 also mounted in the frame 40. The forward end 47 of the latch 46 extends forwardly of the lower end of the actuating bar 16 and fits into a slot 49 (Figs. 2, 4 and 8) formed in the upper portion of a tool carrier 54 which carries at its lower end the operating tool 34. The tool carrier 54 slides in ways

formed in the lower portion of the frame 40, the carrier being held in these ways by plates 51 secured to the frame 40 by screws 53. When the actuating bar 16 is moved downwardly, the tool carrier 54 and the tool 34 are moved downwardly until the tool 34 penetrates the work piece and strikes the bottom plate of a last or the horn button on the work support. The resistance to movement of the tool carrier 54 then becomes greater than the pressure of the spring 50 against the latch 46 thus permitting the latch 46 to move rearwardly, thus causing relative movement between the actuating bar 16 and the tool carrier 54.

When the parts of the device are in the position shown in Fig. 4, a bell crank lever 56 pivotally secured to the lower end of the actuating bar 16 and having a pair of arms carrying cam rolls 64 is in position to engage cam surfaces 58 on cam members 60 secured to the sides of the frame 40. The other arm 57 of the bell crank lever 56 fits into a slot 62 in the tool carrier 54. When the cam rolls 64 on the lever 56 engage the cam surfaces 58, the bell crank lever 56 is rotated in a clockwise direction, thereby moving the tool carrier 54 upwardly. During this time the actuating bar 16 has been moving downwardly so that another pair of cam surfaces 66 on the cam member 60 engage cam surfaces 68 formed on the bell crank lever 56, thereby continuing the upward movement of the tool carrier 54 until the projecting portion 47 of the latch 46 engages a notch 70 formed in the rear surface of the tool carrier 54 and the upper edge or surface of the tool carrier 54 engages a forwardly extending projection 72 on the actuating bar 16.

The extreme lower end of the actuating bar 16 is provided with a cam member 73 for moving the transfer plate 26 forwardly to bring the hole 27 in the transfer plate and the fastening contained therein into alinement with the tool 34. The transfer plate 26 is provided with a block 74 having an inclined upper surface 76 which is engaged by an inclined cam surface 78 formed on the lower portion of the cam member 73. At the time when the inclined surface 76 on the block 74 engages the cam surface 78, the tool 34 has been withdrawn from the work and out of the path of movement of the transfer plate 26. Continued downward movement of the actuating bar 16 then moves the transfer plate 26 forwardly in ways 80 formed in the presser plate 42. This forward movement of the transfer plate 26 continues until the fastening-receiving hole 27 is in alinement with the tool 34.

With the parts of the device in the position just described, the actuating bar 16 continues its downward movement to insert a fastening in the work. The tool 34 is moved downwardly to the position shown in Fig. 5 with the end of the tool 34 flush with the surface of the work to insert a fastening in the work. The parts of the fastening inserting device are now in the position which they occupy during a portion of the return movement of the actuating bar 16. The parts of the device move upwardly as a unit until the upper surface of the tool carrier 54 strikes a stop 82 formed on the lower end of the cover plate 39. During this portion of movement of the actuating bar the transfer plate 26 has been returned to its initial position by the engagement of a cam surface 84 with a cam surface 86 on a block 87 formed on the slide 26, the surfaces being so arranged that upward movement of the actuating

bar will cause the transfer plate 26 to be moved to the left back to the position shown in Fig. 2.

When the tool carrier 54 engages the stop 82, the actuating bar 16 continues its upward movement, forcing the forward end 47 of the latch 46 out of the notch 78 in the tool carrier 54, thus permitting the parts to move relatively to each other until the forward portion 47 of the latch 46 enters the slot 49 in the upper portion of the tool carrier 54. The parts of the device are now in a position to perform another cycle of operation.

The machine is provided with a work support 88 (Fig. 1) which may be of the type disclosed in Letters Patent of the United States No. 1,291-754, granted January 21, 1919, on application of Matthias Brock, above referred to. The work support 88 is provided either with a horn button or with a last pin. The work support 88 is mounted on a vertically movable post 92 which is mounted in bearings 94 and 96 secured to the front of the column 10 and is adapted to be moved upwardly upon depression of a treadle 98, as will be made apparent from an inspection 25 of the drawings of the patent just mentioned above. The lower portion of the post 92 is provided with a pair of rollers 102 which are engaged by inclined surfaces formed on wedges 104 which are moved forwardly by bell crank levers 106 connected by a link 108 to a cam formed in the head of the machine.

Although the construction and operation of the parts of the machine have been described in detail it may be well at this point to review briefly 35 the operation of the machine. When the clutch actuating treadle is depressed the machine is put into operation and the actuating bar 16 moves downwardly under the influence of the spring 32. The end 47 of the latch 46 is in engagement with 40 the tool carrier 54, as shown in Fig. 2, and the tool 34 is moved toward the work to form a fastening receiving hole. When the tool 34 meets an excessive resistance, the latch 46 yields and the tool 34 and the tool carrier 54 come to rest. 45 The actuating bar 16 continues its downward movement and the cam rolls 64 on the bell crank lever 56 engage the cam surfaces 58, thereby causing the bell crank lever 56 to move in a clockwise direction to withdraw the tool 34 from the 50 work. At this time the inclined surface 78 on the lower end of the actuating bar 16 engages the inclined surface 76 on the block 74 which moves the plate 26 to sever a fastening and to transfer the fastening into the path of movement of the 55 tool 34. After the tool 34 has been withdrawn from the work the upper part of the tool carrier 54 is engaged by a projection 72 on the actuating bar 16. The actuating bar 16 and the carrier 54 then move downwardly as a unit to insert a 60 fastening in the hole in the work piece. After the fastening has been inserted the actuating bar and the connections to the tool carrier 54 are moved upwardly until the tool carrier 54 strikes the stop 82. The actuating bar 16 continues its 65 upward movement until the parts of the machine are in the position shown in Fig. 2 and during return movement of the actuating bar 16 the plate 26 is returned to its original position. The machine stops with the parts in readiness to perform another cycle of operations.

Having thus described my invention, what I claim as new and desire to secure by Letters Patent of the United States is:

1. In a fastening inserting machine, an operating tool, means arranged for movement toward

a work piece for reciprocating said tool, and connections between said tool and said means including a member yieldingly connected to said tool and adapted to move relatively to said tool after the tool has penetrated the work piece to 5 form a fastening receiving hole, thereby permitting the tool to be withdrawn from the work during the early portion of the movement of said reciprocating means toward the work, and means acting during a later portion of said movement to move the tool toward the work to insert a fastening in said hole.

2. In a fastening inserting machine, a tool operating both as an awl and as a driver, a carrier for said tool, power-operated means arranged 15 for movement toward a work piece for reciprocating said carrier, and connections between said carrier and said reciprocating means including a member engaging said carrier adapted to yield to permit the tool to move relatively to the member to withdraw the tool from the work piece after the tool has penetrated the work piece to form a fastening receiving hole therein during the early portion of the movement of said reciprocating means toward the work, and means 20 acting during a later portion of said movement to move the tool toward the work to insert a fastening in said hole.

3. In a fastening inserting machine, a tool acting both as an awl and as a driver, a carrier for 30 said tool, a reciprocating bar arranged for reciprocating movement toward and away from a work piece, means for reciprocating said bar, connections between said carrier and said bar including a member carried by said bar and 35 engaging said carrier, said member being adapted to yield when the tool meets an excessive resistance at the conclusion of its work penetrating stroke to permit the tool to be withdrawn from the work during the early portion of the movement of said bar toward the work, and means carried by said bar and engaging said tool carrier to move the tool toward the work during a later portion of said movement to insert a fastening 40 in said hole.

4. In a fastening inserting machine, a tool acting both as an awl and as a driver, a carrier for said tool, a reciprocating bar movable toward a work piece, means for reciprocating said bar, connections between said carrier and said bar including a latch carried by said bar and engaging said carrier, said latch being constructed and arranged to yield when the tool meets an excessive resistance during its work penetrating movement, means carried by said bar constructed and arranged to withdraw the tool from the work during the early portion of the movement of said bar toward the work, and means on said bar for engaging said carrier to move the tool toward 50 the work to insert a fastening during a later portion of said movement.

5. In a fastening inserting machine, a tool operating both as an awl and as a driver, a member arranged for movement toward and away 65 from a work piece for reciprocating said tool, connections between said tool and said member constructed and arranged to reciprocate the tool to form a fastening receiving hole in the work piece, to withdraw the tool from the work during 70 the early portion of the movement of said reciprocating member toward the work, and to move said tool toward the work during a later portion of said movement to insert a fastening in said hole, means for forming and feeding a fastening 75

into the path of movement of said tool, and means for feeding a strip of fastening material to said fastening forming and feeding means.

6. In a fastening inserting machine, a tool operating both as an awl and as a driver, a member arranged for movement toward and away from a work piece for reciprocating the tool, connections between said tool and said member constructed and arranged to reciprocate the tool to form a fastening receiving hole in the work, to withdraw the tool from the work during the early portion of the movement of said reciprocating member toward the work, and to move the tool toward the work during the later portion of said movement to insert a fastening in said hole, means for severing a fastening from a length of fastening material, and a member constructed and arranged to be connected to said reciprocating member to move said severing means thereby to sever a fastening and to transfer the fastening into the path of movement of said tool prior to the fastening inserting operation.

7. In a fastening inserting machine, an operating tool, means for severing a fastening from a length of fastening material and for moving the fastening into the path of movement of said operating tool, means movable toward and away from a work piece for reciprocating said tool, and connections between said tool and said reciprocating means including a member connected to said tool and adapted to move relatively to said tool thereby to permit the tool to be withdrawn from the work after the tool has penetrated the work to form a fastening receiving hole in the work during the early portion of the movement of said reciprocating means toward the work, and means acting during a later portion of said movement to insert a fastening in said hole.

8. In a fastening inserting machine, a tool operating both as an awl and as a driver, a member movable toward and away from a work piece for reciprocating said tool, connections between said tool and said member constructed and arranged to reciprocate the tool to form a fastening receiving hole in the work, to withdraw the tool from the work during the early portion of the movement of said reciprocating member toward the work, and to move the tool toward the work during a later portion of said movement to insert a fastening in said tool, means for forming a fastening and for moving the fastening into the path of movement of said tool, and means on said reciprocating member constructed and arranged to move said fastening forming means and the fastening therein into the path of movement of said tool after said tool has been withdrawn from the work.

9. In a fastening inserting machine, an operating tool, means movable toward and away from a work piece for reciprocating said tool, means for forming and feeding a fastening into the path of movement of said tool when said tool is operating to insert a fastening, and connections between said tool and said means including a member yieldingly connected to said tool and adapted to move relatively to said tool after the tool has penetrated the work to form a fastening receiving hole therein thereby permitting the awl to be withdrawn from the work during the early portion of the movement of said reciprocating means toward the work, and means acting during a later portion of said movement to move the tool toward the work to insert a fastening in said hole.

10. In a fastening inserting machine, a tool operating both as an awl and as a driver, means for forming and feeding a fastening into the path of movement of said tool when said tool is operating as a driver, a carrier for said tool, power operated means movable toward a work piece for reciprocating said carrier, and connections between said carrier and said reciprocating means including a member engaging said carrier adapted to yield to permit the tool to move relatively to the reciprocating member after the tool has penetrated the work to form a fastening receiving hole therein during the early portion of movement of said reciprocating means toward the work, and means acting during a later portion of said movement to move the tool toward the work to insert a fastening in said hole.

11. In a fastening inserting machine, a tool acting both as an awl and as a driver, a carrier for said tool, means for forming and feeding a fastening into the path of movement of said tool when said tool is operating as a driver, a reciprocating bar arranged for movement toward and away from a work piece, means for reciprocating said bar, and connections between said bar and said carrier including a latch carried by one of and engaging the other of those elements, said latch being constructed and arranged to yield when the tool meets an excessive resistance during its movement to form a fastening receiving hole in the work piece, means carried by said bar constructed and arranged to withdraw the tool from the work during the early portion of the movement of said bar toward the work, and means on said bar for engaging said carrier to move the tool toward the work to insert a fastening during a later portion of said movement.

12. In a fastening inserting machine, a tool operating both as an awl and as a driver, a carrier for said tool, an actuating bar arranged for movement toward and away from a work piece, a frame in which said carrier and said bar are reciprocated, and connections between said bar and said carrier constructed and arranged to reciprocate the tool to penetrate the work to form a fastening receiving hole to withdraw the tool from the work during the early portion of the movement of the actuating bar toward the work, and to insert a fastening in said hole during a later portion of said movement, said connections including a latch mounted on said bar and adapted to yield to permit relative movement between the actuating bar and the tool after the tool has penetrated the work, and cam operated means on said bar for withdrawing the tool from the work.

13. In a fastening inserting machine, a tool operating both as an awl and as a driver, a carrier for said tool, an actuating bar arranged for movement toward and away from a work piece, a frame in which said carrier and said bar are reciprocated, and connections between said bar and said carrier constructed and arranged to reciprocate the tool to penetrate the work to form a fastening receiving hole to withdraw the tool from the work during the early portion of the movement of the actuating bar toward the work piece, and to insert a fastening in said hole during a later portion of said movement, said connections including a latch mounted on said bar and adapted to yield to permit relative movement between the actuating bar and the tool after the tool has penetrated the work, cam operated means on said bar for withdrawing the tool

from the work, and means secured to said bar for moving the tool toward the work to insert a fastening in said hole during a later portion of said movement of the actuating bar.

5 14. In a fastening inserting machine, a tool operating both as an awl and as a driver, a carrier for said tool, means movable toward and away from a work piece for reciprocating said carrier, and connections between said carrier and 10 said reciprocating means including a latch arranged to transmit movement to the tool carrier during the early part of the movement of said reciprocating means toward the work piece to cause the tool to form a fastening receiving hole 15 in the work piece, means arranged to return the tool carrier to its original position, and means carried by the reciprocating means for moving the tool toward the work to insert a fastening in said hole during a later portion of said movement of 20 said reciprocating means toward the work.

15. In a fastening inserting machine, a tool operating both as an awl and as a driver, a carrier for said tool, means movable toward a work piece for reciprocating said carrier, and connections between said carrier and said reciprocating means including a latch arranged to transmit movement of said reciprocating means to the tool carrier during the early part of the movement of said reciprocating means toward the work piece to cause the tool to form a fastening receiving hole in the work piece, a spring normally maintaining said latch in engagement with the tool carrier and adapted to yield when the tool meets an excessive resistance during its work penetrating stroke to permit relative movement between the tool carrier and the reciprocating means, means arranged to return the tool carrier to its original position, and means carried 30 by the reciprocating means for moving the tool toward the work to insert a fastening in said hole during a later portion of said movement.

16. In a fastening inserting machine, a tool operating both as an awl and as a driver, a carrier for said tool, means movable toward and away from a work piece for reciprocating said carrier, and connections between said carrier and said reciprocating means including a latch arranged to transmit movement to the tool carrier during the early part of the movement of said reciprocating means toward the work piece to cause the tool to form a fastening receiving hole in the work piece, a bell crank lever fulcrumed to said reciprocating means and having an arm 45 in engagement with the tool carrier, said lever being arranged to return the tool carrier to its original position after the tool has penetrated the work, and means carried by the reciprocating means for moving the tool toward the work to insert a fastening in said hole during a later portion of said movement.

17. In a fastening inserting machine, a tool operating both as an awl and as a driver, a carrier for said tool, means movable toward the work piece for reciprocating said carrier, connections between said carrier and said reciprocating means including a latch arranged to transmit movement to the tool carrier during the early part of the movement of said reciprocating means toward the work piece to cause the tool to form a fastening receiving hole in the work piece, means arranged to return the tool carrier to its original position, means carried by the reciprocating means for moving the tool toward the work to insert a fastening in said hole during a

later portion of said movement, means for forming a fastening and for moving the fastening into the path of movement of said tool, and means on said reciprocating member constructed and arranged to move said fastening forming means 5 and the fastening therein into the path of movement of said tool after said tool has been withdrawn from the work.

18. In a fastening inserting machine, a tool operating both as an awl and as a driver, a carrier for said tool, means movable toward a work piece for reciprocating said carrier, and connections between said carrier and said reciprocating means including a latch arranged to transmit movement to the tool carrier during the early 10 part of the movement of said reciprocating means toward the work piece to cause the tool to form a fastening receiving hole in the work piece, a spring normally maintaining said latch in engagement with the tool carrier and adapted to yield when the tool meets an excessive resistance during its work penetrating stroke to permit relative movement between the tool carrier and the reciprocating means, a bell crank lever fulcrumed to said reciprocating means having an arm in 15 engagement with the tool carrier, said lever being arranged to return the tool carrier to its original position after the tool has penetrated the work, and means carried by the reciprocating means for moving the tool toward the work to insert a 20 fastening in said hole during a later portion of said movement.

19. In a fastening inserting machine, a tool operating both as an awl and as a driver, a carrier for said tool, means movable toward a work 35 piece for reciprocating said carrier, means for moving a fastening into the path of movement of said tool when said tool is operating as a driver, and connections between said carrier and said reciprocating means including a latch arranged 40 to transmit movement to the tool carrier during the early part of movement of said reciprocating means toward the work piece to cause the tool to form a fastening receiving hole in said work piece, a spring normally maintaining said 45 latch in engagement with the tool carrier and adapted to yield when the tool meets an excessive resistance during its work penetrating stroke to permit relative movement between the tool carrier and the reciprocating means, means arranged 50 to return the tool carrier to its original position, and means carried by the reciprocating means for moving the tool toward the work to insert a fastening in the fastening receiving hole during a later portion of said movement.

20. In a fastening inserting machine, a tool operating both as an awl and as a driver, a member movable toward and away from a work piece for reciprocating said tool, connections between said tool and said member constructed and arranged to reciprocate the tool to form a fastening receiving hole in the work piece, to withdraw the tool from the work during the early portion of the movement of said reciprocating member toward the work, and to move said tool toward 65 the work during a later portion of said movement to insert a fastening in said hole, a plate having a hole to receive the end of a length of fastening material, a member secured to said reciprocating member having an inclined surface, 70 and means on said plate having a surface arranged to be engaged by the inclined surface on said last-mentioned member to move said plate to sever a fastening from the length of fastening material and to move the severed fastening into 75

the path of movement of said tool after the tool has been withdrawn from the work.

21. In a fastening inserting machine, a tool operating both as an awl and as a driver, a carrier for said tool, an actuating bar arranged for movement toward and away from a work piece, a frame in which said bar and said carrier are reciprocated, connections between said bar and said carrier including a latch arranged to transmit movement to said carrier during the early part of the movement of said bar toward the work piece to cause the tool to form a fastening receiving hole in the work piece, a cam carried by said frame, a bell crank lever arranged to engage said cam to withdraw the tool from the work after the tool has formed the fastening receiving hole, and means carried by the bar for moving the tool toward the work during a later portion of said movement to insert a fastening in said hole.

22. In a fastening inserting machine, a tool operating both as an awl and as a driver, a carrier for said tool, means arranged for movement toward and away from a work piece for reciprocating said carrier, a latch carried by said reciprocating means arranged to transmit movement of said reciprocating means to said tool carrier during the early portion of the movement of said reciprocating means toward the work piece to cause the tool to form a fastening receiving hole in the work piece, means for moving the tool carrier relatively to the reciprocating means to withdraw the tool from the work, and means carried by the reciprocating means arranged to move the tool toward the work to insert a fastening in said hole during a later portion of said movement.

23. In a fastening inserting machine, a tool operating both as an awl and as a driver, a carrier for said tool, means arranged for movement toward and away from a work piece for reciprocating said carrier, a latch arranged to transmit movement of said reciprocating means to said tool carrier during the early portion of the movement of said reciprocating means toward the work piece to cause the tool to form a fastening receiving hole in the work piece, a bell crank lever for moving the tool relatively to the reciprocating means to withdraw the tool from the work, and means carried by the reciprocating means arranged to move the tool toward the work to insert a fastening in said fastening receiving hole during a later portion of said movement.

24. In a fastening inserting machine, a tool operating both as an awl and as a driver, a carrier for said tool, means for reciprocating said carrier, a plate having a hole to receive the end of a length of fastening material, a member secured to said reciprocating means having an inclined surface, and means on said plate having a surface arranged to be engaged by the inclined surface on said last-mentioned member to move said plate thereby to sever a fastening from a length of fastening material and to move the severed fastening into the path of movement of said tool prior to the fastening inserting operation.

25. In a fastening inserting machine, a tool operating both as an awl and as a driver, a carrier for said tool, means arranged for movement toward and away from a work piece for reciprocating said carrier, means carried by said reciprocating means arranged to transmit movement of said reciprocating means to said tool carrier

during the early portion of the movement of said reciprocating means toward the work piece to cause the tool to form a fastening receiving hole in the work piece, a bell crank lever for moving the work carrier relatively to the reciprocating means to withdraw the tool from the work, and means carried by the reciprocating means constructed and arranged to move the tool toward the work to insert a fastening in said fastening receiving hole during a later portion of said movement.

26. In a fastening inserting machine, a tool operating both as an awl and as a driver, a carrier for said tool, means arranged for movement toward and away from a work piece for reciprocating said carrier, a supporting member in which said carrier and said reciprocating means are arranged to slide, means carried by said reciprocating means arranged to transmit movement of said reciprocating means to said tool carrier during the early portion of the movement of said reciprocating means toward the work piece to cause the tool to form a fastening receiving hole in the work piece, cam members carried by said supporting member, a bell crank lever adapted to engage said cams to withdraw the tool from the work, and means carried by the reciprocating means arranged to move the tool toward the work to insert a fastening in said fastening receiving hole during a later portion of said movement.

27. In a fastening inserting machine, a tool operating both as an awl and as a driver, a carrier for said tool, means arranged for movement toward and away from a work piece for reciprocating said carrier, a supporting frame in which said carrier and said tool are reciprocated, a latch carried by said reciprocating means arranged to transmit movement of said reciprocating means to the tool carrier during the early portion of the movement of said reciprocating means toward the work piece to form a fastening receiving hole in the work piece, a spring normally maintaining said latch in engagement with said carrier and arranged to yield to permit relative movement between the tool carrier and the reciprocating means after the tool has formed a fastening receiving hole in the work piece, cams carried by said frame, a bell crank lever pivoted to said reciprocating means and having cam rolls on one arm arranged to engage said cam surfaces after the tool has penetrated the work, said lever having another arm engaging the tool carrier and arranged to withdraw the tool from the work, and means carried by the reciprocating means arranged to engage the tool carrier to move the tool toward the work to insert a fastening in said hole during a later portion of said movement.

28. In a fastening inserting machine, a tool operating both as an awl and as a driver, a carrier for said tool, means movable toward a work piece for reciprocating said carrier, a latch arranged to transmit movement of said reciprocating means to said tool carrier during the early portion of the movement of said reciprocating means toward the work piece to cause the tool to form a fastening receiving hole in the work piece, a bell crank lever for moving the tool carrier relatively to the reciprocating means to withdraw the tool from the work, and means carried by the reciprocating means arranged to move the tool toward the work to insert a fastening in said fastening receiving hole during a later portion of said movement.

29. In a fastening inserting machine, a tool op-

erating both as an awl and as a driver, a carrier for said tool, means movable toward and away from a work piece for reciprocating said carrier, a supporting frame in which said carrier and said tool are reciprocated, a latch carried by said reciprocating means arranged to transmit movement of said reciprocating means to the tool carrier during the early portion of the movement of said reciprocating means toward the work piece to form a fastening receiving hole in the work piece, a spring normally maintaining said latch in engagement with said carrier and arranged to yield to permit relative movement between the tool carrier and the reciprocating means after the tool has formed a fastening receiving hole in the work piece, a cam carried by said frame, a bell crank lever pivoted to said reciprocating means and having a cam roll on one of its arms arranged to engage said cam surfaces after the tool has penetrated the work, said lever having another arm engaging the tool carrier and arranged to withdraw the tool from the work, and a projection formed on said reciprocating means arranged to engage the tool carrier to move the tool toward the work to insert a fastening in said hole during a later portion of said movement.

30. In a fastening inserting machine, a tool operating both as an awl and as a driver, a carrier for said tool, means arranged for movement toward and away from a work piece for reciprocating said carrier, a latch arranged to transmit movement of said reciprocating means to said tool carrier during the early portion of the movement of said reciprocating means toward the work piece to cause the tool to form a fastening receiving hole in the work piece, a bell crank lever for moving a tool relatively to the reciprocating means to withdraw the tool from the work, means carried by the reciprocating means arranged to move the tool toward the work to insert

a fastening in said fastening receiving hole during a later portion of said movement, a plate having a hole arranged to receive the end of a length of fastening material, a member secured to said reciprocating means, and means on said plate having a surface arranged to be engaged by the inclined surface on said last-mentioned member to move said plate to sever a fastening from a length of fastening material and to move the severed fastening into the path of movement of said tool prior to the fastening inserting operation. 5 10

31. In a fastening inserting machine, a tool operating both as an awl and as a driver, a carrier for said tool, means movable toward and away from a work piece for reciprocating said carrier, means for severing a fastening from a length of fastening material, and a member connected to said reciprocating member constructed and arranged to move said severing means to sever a fastening and to transfer the fastening into the path of movement of said tool prior to the fastening inserting operation, and connections between said carrier and said reciprocating means including a latch constructed and arranged to transmit movement of the tool carrier during the early part of the movement of said reciprocating means toward the work piece to cause the tool to form a fastening receiving hole in said work piece, a spring normally maintaining said latch in engagement with the tool carrier and arranged to yield when the tool meets an excessive resistance during its work penetrating stroke to permit relative movement between the tool carrier and the reciprocating means, means arranged to return the tool carrier to its original position, and means carried by the reciprocating means for moving the tool toward the work to insert a fastening in the fastening receiving hole during a later portion of said movement. 15 20 25 30 35
